UNITED STATES PATENT OFFICE

SWINFEN BRAMLEY-MOORE, OF WHITE PLAINS, NEW YORK, ASSIGNOR TO BRAMLEY MACHINERY CORPORATION, OF NEW YORK, N. Y., A CORPORATION OF NEW YORK

CRUSHING, GRINDING, AND REFINING MACHINE

Application filed June 18, 1929. Serial No. 371,817.

The present invention relates to crushing, grinding and refining machines, such as are used for crushing, grinding or refining chocolate, paint, printer's ink and other materials, and this invention is an improvement over the machine disclosed in my Patent No. 1,692,884, granted November 27, 1928.

One object of the invention is the provision of novel means for mounting and applying pressure to the grinding elements of the rotor or movable part of the machine.

Another object is to simplify the construction of the mounting and adjusting means for the grinding elements.

15 A further object is the provision of a novel grinding surface with which the grinding elements are cooperable for effectively crushing, grinding, or refining the material.

With the foregoing and other objects in view, which will be apparent as the description proceeds, the invention resides in the construction and arrangement of parts, as hereinafter described and claimed, it being understood that changes can be made within 25 the scope of what is claimed, without departing from the spirit of the invention.

The invention is illustrated in the accompanying drawings, wherein—

Figure 1 is a vertical median section of the 30 improved machine, portions being shown in elevation.

Fig. 2 is a section on the line 2—2 of Fig. 1.

Fig. 3 is a sectional detail of a modified construction.

35 Fig. 4 is a section on the line 4—4 of Fig. 3.

Fig. 5 is a diametrical sectional detail of another modification.

Fig. 6 is a cross-sectional detail of the construction shown in Fig. 5.

40 The casing comprises the cylindrical body 11 and end plates or heads 12 and 13. The end plate or head 12 has an inlet 14 near the top of the casing which is disposed with its axis horizontal, and said end plate has the 45 hopper 15 into which the material is dumped

to flow through said inlet into the casing. The end plate or head 13 may also have an inlet and hopper if desired.

A water jacket 16 surrounds the body 11 for the circulation of water therein to cool 50 the body, or conversely for the circulation of a heating medium.

The inner surface of the body 11 has welded thereto, as at 17, rods 18, forming a ribbed or corrugated grinding surface. 55 The rods 18 are disposed longitudinally, parallel with the axis of the body, and are arranged in any suitable number of annular sets, contacting side by side. As shown, there are three sets or groups of rods, one for 60 each section of the rotor. The ends of the rods are welded, as at 17, to the body 11, thereby holding said rods securely to the inner surface of the body. The grinding surface of the body is thus conveniently produced by welding the rods therein, and the grinding surface thus produced is effective 65 for crushing, grinding or refining the material.

The end plate 13 has a normally closed outlet 19 near the bottom of the casing, through 70 which the material may be discharged.

The end plate 12 has a bearing 20 through which a tubular or sleeve shaft 21 is journaled, and a spindle 22 extends through the 75 shaft 21.

A wheel or spider 23 is secured on the inner terminal of the shaft 21 within the casing and forms the body of the rotor. Slides 24 are movable radially in slots 26 in the 80 ends of the arms of the spider 23, and thrust rods 27 are slidable radially in said arms and have their outer terminals seated in sockets 25 in the slides 24. The inner terminals of said rods are slidable within a 85 cage 28 fitted within the spider 23 and having balls 29 therein against which the inner ends of said rods abut.

A cone or tapered cam 30 is secured to the inner end of the spindle 22 and is mov- 90

able between the balls 9, so that when the spindle is forced inwardly the cone being projected between the balls 29 will force said balls apart, thereby forcing the rods 27 outwardly. When the spindle is retracted the cone 30 is withdrawn, thereby permitting the balls 29 and rods 27 to move inwardly. A cap 30' is secured to the spider 23 for holding the cage 28 in place and to also enclose the balls 29 and cone 30.

10 The grinding elements shown in Figs. 1 and 2 are similar to those disclosed in Patent No. 1,692,884. Longitudinal rods 32 extend through the slides 24, and double leaf 15 springs 33 have their intermediate portions secured to blocks 34 mounted for oscillation on said rods.

20 The ends of said springs 33 are suitably connected, as at 35, with cross members 36 having the grinding rods or elements 38 secured thereto.

25 As seen in Fig. 1, there are three sections of the rotor, each containing several groups of grinding elements, and each group comprises a pair of leaf springs 33, carrying two pairs of members 36, and each pair of members has two rods 38.

30 The pressure is distributed from the springs 33 to the rods 38, and the springs 33 may flex and also oscillate on the rods 32 to distribute the pressure between the two pairs of rods of each group. Therefore, when the spindle 22 is forced inwardly to force the rods 27 outwardly, the pressure 35 is distributed uniformly from the slides 24 to the rods 38 by way of the rods 32, springs 33 and members 36. The pressure is relieved when the spindle 22 is retracted.

40 The machine is driven by a gear wheel 44 secured on the shaft 21 at the outer side of the plate 12, and said plate is formed with a housing 45 for said gear wheel having the removable cover 46 in which the shaft 21 is journaled. Anti-friction thrust bearings 45 47 and 48 are provided to take up end thrusts of the shaft 21 in opposite directions.

50 A tubular screw 48 is secured to the housing cover 46, and a hand wheel 50 has a bushing 51 threaded on said screw, for moving the hand wheel axially when it is rotated. An annular plate 52 is secured to the hub of the hand wheel and is disposed between a pair of anti-friction thrust bearings 53 secured on the outer terminal of the spindle 22 by means of the nut or retaining element 54, whereby the spindle 22 is moved inwardly and outwardly by rotating the hand wheel which travels inwardly and outwardly by screw action. The swivel connection between the spindle and hand wheel permits the spindle to rotate with the shaft 21.

60 A cap 55 is secured to the hand wheel 50 with the plate 52 to house and protect the

bearings 53 and outer terminal of the spindle.

70 The spindle 22 may be adjusted during the operation of the machine by merely rotating the hand wheel 50, so that the pressure on the grinding rods 38 may be regulated.

75 The rods 38 being moved across the fixed rods 18 will provide an effective grinding action. As shown, the rods 38 are of larger diameter than the rods 18.

80 Figs. 3 and 4 illustrate a modification. An elongated slide 24^a is slidably mounted between its ends in the slot 26^a of each arm of the spider 23^a, and rods 33^a pass slidably through said slide 24^a and are suitably connected at their ends, as at 35^a, with the members 36^a to which the grinding rods 38^a are secured. The thrust rod 27^a has a terminal of reduced diameter entering the socket 25^a in the slide 24^a, and a bowed leaf spring 60 has its terminals bearing against the inner surface of the slide 24^a and its intermediate portion has an aperture through which the reduced terminal 85 of the rod 27^a extends, a collar 61 being disposed on said terminal between the shoulder of the rod and the spring 60, so that when the rod is forced outwardly it applies a straightening-out pressure to the spring 60, and the terminals of the spring press against the slide 24^a, thereby applying the pressure to the rods 33^a, members 36^a and rods 38^a.

90 The rods 33^a are slidably loose in the slide 24^a, and the members 36^a in front of the slide 24^a contact at their rear ends with said slide, to move the members 36^a and rods 38^a with the slide 24^a when the rotor is rotated, the rear members 36^a being pulled 95 with the rods 33^a.

100 Both constructions are such that when the rods 27 and 27^a are retracted they will release the slides 24 and 24^a, respectively, to permit them being removed from the spiders, thereby 105 enabling the groups of grinding elements to be readily removed for repair or replacement.

110 As shown in Figs. 5 and 6, the springs 33^b extend across bars 32^b and are clamped between said bars and clamp plates 34^b. The intermediate portions of the bars 32^b are slideable in the slots 26^b of the spider 23^b and have plates or blocks 24^b secured thereto and sliding in said slots. Said blocks have sockets 25^b receiving the outer ends of the rods 27^b and 115 containing wear pieces 25' against which the rods abut.

120 The other parts 21^b, 22^b, 28^b, 29^b, 30^b, 35^b, 36^b and 38^b are substantially the same as the corresponding parts in the constructions hereinbefore described.

125 Having thus described the invention, what is claimed as new is:

130 1. In a grinding machine, a body, and rods disposed side by side and having their ends

- welded to said body to provide a ribbed grinding surface, said rods being disconnected between their ends from said body.
2. In a grinding machine, a cylindrical body, and rods disposed side by side against the inner surface of said body longitudinally thereof and having their ends welded to said body, to provide a ribbed grinding surface, said rods being disconnected between their ends from said body.
3. A grinding machine comprising a cylinder, a shaft rotatable therein, a member on said shaft within the cylinder, slides mounted for radial movement in said member, grinding elements carried by said slides to work within the cylinder, rods slidable radially in said member for moving said slides outwardly, and a spindle slidable in said shaft and operably connected with said rods to move same outwardly.
4. A grinding machine comprising a cylinder, a shaft rotatable therein, a member on said shaft having slots, slides movable in said slots, grinding elements mounted on said slides to work in said cylinder, rods slidable in said member, said slides having sockets receiving said rods, and a spindle slidable in said shaft and operably connected with said rods to move them outwardly.
5. A grinding machine comprising a cylinder, a shaft rotatable in said cylinder, a member mounted on said shaft within the cylinder, slides movable radially in said member, grinding elements mounted on said slides to work within the cylinder, rods slidable radially in said member and arranged to move said slides outwardly, and a spindle slidable in said shaft and having a cone operably related with said rods for sliding the rods outwardly.
6. A grinding machine comprising a cylinder, a shaft rotatable in said cylinder, a member mounted on said shaft within the cylinder, slides movable radially in said member, grinding elements mounted on said slides to work within the cylinder, rods slidable radially in said member and arranged to move said slides outwardly, a spindle slidable in said shaft and having a cone movable between said rods, and balls disposed between said cone and rods.
7. A grinding machine comprising a cylinder, a shaft rotatable therein, a member mounted on the shaft within the cylinder, slides movable radially in said member, grinding elements mounted on said slides to work within said cylinder, a cage assembled with said member, rods slidable radially in said member and cage and arranged to move said slides outwardly, a spindle slidable in said shaft and having a cone movable in said cage, and balls in said cage between said cone and rods.
8. A grinding machine comprising a cylinder, a member rotatable in said cylinder and
- having radial slots, slides movable in said slots, grinding elements mounted on said slides to work within the cylinder, rods slidable radially in said member, said slides having sockets to receive the outer terminals of said rods, and means for moving said rods outwardly.
- In testimony whereof I hereunto affix my signature.
- SWINFEN BRAMLEY-MOORE.
